HAND-TOOL.

1,162,439.

Specification of Letters Patent. Patented Nov. 30, 1915.

Application filed April 4, 1914. Serial No. 829,671.

To all whom it may concern:

Be it known that I, WILLIAM A. BERNARD, a citizen of the United States, residing in the city and county of New Haven and State 5 of Connecticut, have invented certain new and useful Improvements in Hand-Tools, of which the following is a full, clear, and exact description.

This invention relates to hand presses, 10 hand punches, or other tools, of that type in which the device is operated to stamp or punch metal blanks, and the like, by manipulation of one or more lever members or handles with which the tool is equipped.

15 I shall describe my improvements as applied to a hand tool for embossing purposes, but it will be apparent from the following description that various features of the invention are applicable to tools and devices 20 of other types.

The primary object of the invention is to furnish a tool wherein a maximum amount of power may be developed by convenient manual manipulation of the operating parts, 25 and wherein the size of the device is very small in comparison to the power developed.

In the form of the invention which I have selected for illustration, the tool is adapted 30 to emboss a steel band or strip with several good sized figures, or other characters, at one operation, which may be performed with the expenditure of very little energy on the part of the operator; and yet the tool is of such size and shape as to be easily portable, 35 and to fit readily in the workman's pocket. This result is brought about by novel means for operating one of the movable parts of the tool by a lever handle, or handles, as hereinafter described.

40 I also contemplate the provision of a tool having improved means to center an interfitting plunger and work support relative to each other as the tool is operated, in case such plunger and support are not already 45 in perfect alinement.

Other objects of the invention are to improve certain details of construction in a hand tool particularly applicable to the stamping or punching of strips of sheet 50 metal; and to improve generally the construction and operation of devices of the class to which my invention relates.

To these and other ends, the invention consists in the novel features and combina-

tions of parts to be hereinafter described 55 and claimed.

In the accompanying drawing, Figure 1 is a front elevation of an embossing tool constructed in accordance with my invention, with the lever handles separated, and 60 the movable member of the embossing mechanism retracted from the fixed member or work support. Fig. 2 is an elevation of the tool, taken from the opposite side, with the handles closed together. Fig. 3 is a side 65 edge view of the tool. Fig. 4 is a top view of Fig. 2. Fig. 5 is a section on line 5—5 of Fig. 1. Figs. 6 and 7 are detail views of the respective embossing members, and Fig. 8 is a section on line 8—8 of Fig. 1. 70

Referring to the drawing, 10 indicates generally the head of the tool, which forms 75 a support for the various parts and is composed of parallel plates 11, 12, secured together in the manner hereinafter described.

Guided lengthwise in the head 10 is a slide or plunger 13 which, in the present tool, acts as one of the embossing members. A member 14 fixed to the head 10 is adapted to support the work to be operated upon and to 80

cooperate with the plunger in embossing the same. The plunger 13 is arranged to move toward and away from the relatively 85 fixed member 14, and said plunger and its coöperating member are appropriately formed at their adjacent surfaces (Figs. 6 and 7) to emboss a piece of metal in the desired manner when it is inserted between them and compressed by manipulation of the plunger. The plunger 13 is guided 90

lengthwise of the head 10, between the plates 11 and 12, by means of bolts 15, 16, which interconnect the plates 11 and 12, as 95 shown in Fig. 5. The plunger has a longitudinal slot 17 through which said bolts extend. The bolt 15 is located near one end of the slot 17, and the bolt 16 is located near the other end of the slot. The slot 17 is slightly longer than the distance from one 100 of the bolt shanks to the other (outside measurement) so that the plunger can have a limited lengthwise movement relative to the bolts, in which movement the plunger is guided by the bolt shanks in an obvious manner.

The bolt 15 limits the movement 105 of the plunger toward the fixed member 14, and the bolt 16 limits the movement of the plunger away from said member, as will be

understood. The member 14 is held in place between the plates 11 and 12 by a single bolt 18 interconnecting said plates, whereby said member may have a slight swinging movement for the purposes presently explained. The head 10 is suitably apertured to permit the introduction between the parts 13, 14 of the metal, or other material to be operated upon. In the form shown, the plates 11 and 12 are provided with registering openings 19, 20, which are located adjacent the embossing face of the member 14, so that when the plunger 13 is retracted from the member 14, as shown in Fig. 1, a strip of metal to be embossed may be inserted between the members 13, 14. By providing the openings 19 and 20, the strips of metal to be embossed can be passed completely through the head 10, if desired.

26 The plunger 13 extends rearwardly beyond the plates 11 and 12, and at its rearwardly extending portion, it is provided (on opposite sides of an imaginary center line running lengthwise of the plunger) with 25 pivots, illustrated as bolts 21, whereby the plunger is pivoted to the forward extremities of operating handles or levers 22. Pins 23, interconnecting the plates 11, 12, at the respective sides of the plunger 13, form 30 pivots for links 24 pivoted between the plates 11, 12. Each pin 23 extends through the forward end of the corresponding link 24, and the rear end portion of such link, which is turned inwardly, as shown at 24^a, 35 is pivoted to one of the lever handles 22 by a pin 25 at a point between the corresponding pivot bolt 21 and the opposite extremity of the handle. Thus the lever handles 22 are pivoted at, or adjacent, their forward 40 ends to the plunger 13, and intermediate of their ends they are pivoted to the rear ends of the respective links 24, which links 24 are in turn pivoted to the head 10, on opposite sides of the path of movement of the 45 plunger. The parts are so arranged that when the lever handles are separated to the full extent permitted by the engagement of the pin 16 with slot 17, the pivotal points 21 are appreciably closer to the center of 50 the plunger (see line 5—5 of Fig. 1) than are the pivotal points 25.

Each lever handle 22 is preferably bent up from sheet metal into substantially U-shaped cross-section, and its forward end 55 portion is cut away to present opposing plates 22^a, between which the rear end of the plunger and the rear end of the corresponding link 24 are interposed. In other words, each lever handle is shaped to straddle the plunger and also the corresponding link 24, whereby strong pivotal connection of the respective parts to each other is facilitated.

60 The operation of the tool is substantially as follows: The lever handles 22 being sep-

arated, as shown in Fig. 1, the strip to be embossed is inserted in the opening 19, between the fixed and movable embossing members. If it is desired to emboss only the end portion of the strip, a suitable stop 70 26, pivoted to the plate 12 by a pin 27, may be projected across the opening 20, as shown in full lines in Fig. 2, so as to arrest the strip in the desired position. As the handles 75 22 are forced together they swing about the pivots 25, whereby the points 21 are moved forwardly, thereby forcing the plunger forwardly, and compressing the strip against the abutment 14. At the same time, the pivotal points 25 move inwardly about the 80 centers of the respective pins 23, each lever 22 forming with its connected link 24 a sort of toggle, and as the pivotal points 25 almost reach lines passing through the respective pivotal points 21 parallel to the longitudinal 85 axis of the plunger, the movement of the plunger is greatly retarded relatively to the movement of the handles, and the power developed is multiplied to a remarkable degree. In fact, the power developed is so 90 great that a hard steel strip of considerable thickness can be embossed over quite a large surface with the expenditure of surprisingly little energy on the part of the operator.

It will therefore be understood that by my 95 invention a rectilinearly movable member, such as the plunger 13, may be so actuated by manipulation of a lever, such as 22, that the plunger is very much retarded at one end of its movement whereby the power 100 transmitted to the work is correspondingly multiplied. This is effected by providing the lever 22, or its equivalent, with a movable fulcrum, such as is afforded by the link 24, whereby the fulcrum of the lever may 105 swing freely in an arc so as not to interfere with the sliding movement of the plunger. The power is increased as the pivotal point 21 and fulcrum 25, in swinging orbitally about each other, almost aline with a plane 110 parallel to the longitudinal axis of the plunger, as will be understood, at which time the movement of the plunger is arrested just before a dead center is reached.

The pivoting of the member 14 on a 115 single pin or bolt 18 enables said member to swing freely to a certain extent so that it will always center itself accurately with respect to the plunger. Thus the parts 13 and 14 will always fit together accurately if they 120 are provided in the first instance with properly shaped interfitting projections and recesses. It is immaterial which of the parts 13, 14 carries the projection or projections, and which part carries the corresponding 125 die or matrix.

If it is desired to take out the abutment or work support 14 for substituting a new one, this can be readily effected by removing the bolt 18 from the head of the tool. 130

Similarly, the plunger 13 can be removed from the tool by removing the bolts 15, 16 and 21. When these last named bolts have been removed, the plunger 13 may be slid 5 out between the lever handles, if the latter are separated. Thus, the tool can be used with several different dies, or the like, which adapt it to different kinds of work. For example, if it is desired to punch holes in 10 the metal strip, a plunger having a suitable punch may be substituted for the plunger 13, and a corresponding die block may be substituted for the abutment or block 14. By the construction described, the tool obviously 15 has a large scope of utility.

I do not limit myself to a tool in which a movable part acting on the blank is operated by two handle levers, and it will be understood that in the broad aspects of the invention 20 the character of the work done by the tool, and the details of the construction, are immaterial. Various changes in these and other respects may be adopted within the scope of my inventive idea as expressed in 25 the claims.

What I claim is:

1. In a hand tool, the combination of a pair of flat plates arranged in spaced parallel relation, a plunger movable lengthwise 30 between said plates and having opposite surfaces in contact with the respective plates, said plunger having a longitudinal slot, a device for fastening the plates together extending through said slot for guiding 35 the plunger, an abutment to coöperate with said plunger, operating levers pivoted to said plunger, and links pivoted between said plates at opposite sides respectively of said plunger and likewise pivoted to said 40 operating levers; substantially as described.

2. In a hand tool, the combination of a pair of flat plates arranged in spaced parallel relation, a plunger movable lengthwise between said plates and having opposite 45 surfaces in contact with the respective plates, said plunger having a longitudinal slot, a device for fastening the plates together extending through said slot for guiding 50 the plunger, an abutment to coöperate with said plunger, operating levers pivoted to said plunger, and links pivoted between said plates at opposite sides respectively of said plunger and likewise pivoted to said 55 operating levers, said operating levers pivoted to said plunger on opposite sides respectively of the lengthwise axis of the plunger; substantially as described.

3. In a hand tool, the combination of a pair of plates arranged in spaced parallel 60 relation, a plunger guided lengthwise between said plates, said plunger having a slot, a fastening pin for securing said plates together, passing through said slot for limiting the movement of the plunger, levers 65 having forked ends straddling the plunger

at opposite sides of the longitudinal axis of the plunger and pivoted to said plunger, links extending alongside of said plunger between said plates in approximate parallelism with the plunger and pivoted between 70 the plates near the forward end of the plunger, said links having inturned ends pivoted to said levers intermediate of the ends of said levers, and a work support secured to said plates and coöperating with said 75 plunger; substantially as described.

4. In a hand tool, the combination of a pair of plates arranged in spaced parallel relation, a plunger guided between said plates, a work support interposed between 80 said plates to coöperate with said plunger, links interposed between said plates on opposite sides respectively of said plunger, operating levers pivoted to said links and to said plunger, fastening devices for 85 securing the plates together, passing through said links and pivoting them to the plates, a fastening device for the plates passing through said work support, and a fastening device for the plates passing through an 90 opening in the plunger; substantially as described.

5. In a hand tool, the combination of a pair of plates arranged in spaced parallel relation, a plunger guided between said 95 plates, a work support interposed between said plates to coöperate with said plunger, links interposed between said plates on opposite sides respectively of said plunger, operating levers pivoted to said links and to 100 said plunger, fastening devices for securing the plates together, passing through said links and pivoting them to the plates, a fastening device for the plates passing through said work support, and a fastening 105 device for the plates passing through an opening in the plunger, said plates having registering openings between the plunger and the work support for the insertion of the material to be operated upon; substantially 110 as described.

6. In a hand tool, the combination of spaced parallel plates, a plunger guided between the same, an abutment for said plunger interposed between said plates, and a 115 single pin extending through said abutment and said plates and forming a mounting on which the abutment may swing into line with the plunger; substantially as described.

7. In a hand tool, the combination of a 120 head comprising spaced parallel plates, said plates having registering cut away portions forming an opening in the head, an abutment between the plates on one side of said opening, a plunger between the plates on the opposite side of said opening, means for operating said plunger and a movable stop associated with said opening at one face of the tool; substantially as described.

8. In a hand tool, the combination of a 125

head comprising a pair of parallel plates, a plunger guided between said plates, means for operating said plunger, an abutment carried by said head to coöperate with said plunger, said plates having registering cut-away portions between said plunger and abutment for the insertion of the material to be operated upon, and a swinging stop carried by the head to limit the insertion

of the material in a direction depthwise of 10 the head; substantially as described.

In witness whereof, I have hereunto set my hand on the 3rd day of April, 1914.

WILLIAM A. BERNARD.
